UNITED STATES PATENT OFFICE.

WILLIAM D. THOMPSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF MICHIGAN.

CAR-WALL CONSTRUCTION.

Application filed September 13, 1926. Serial No. 135,218.

The invention relates to metallic wall constructions for railway cars being more particularly designed for use in the construction of car ends.

5 It is the object of the invention to obtain greater strength with the same weight of metal, and further to facilitate and reduce the cost of manufacture. With these and other objects in view the invention consists 10 in the construction as hereinafter set forth.

In the drawings:

Figure 1 is an elevation of a car end embodying my invention.

Figure 2 is a side elevation thereof.

15 Figure 3 is a vertical cross section on line 3—3 of Figure 1.

Figure 4 is a horizontal section on line 4—4 of Figure 1.

20 Figure 5 is an enlarged cross section of one of the rolled paneled plates of which the wall is constructed.

In the present state of the art, car ends and other car walls of various constructions have been formed from metallic plates 25 pressed to produce corrugations, panels, ribs and other reinforcements. Such reinforced plates are formed from flat metal plates or sheets which originally are of uniform gauge but as an incident to the pressing the 30 metal is drawn in certain portions thereof with the result that the gauge is varying. Furthermore this drawing of the metal often has the effect of weakening the plate at the very point where the greatest strength is required so that the total strength of the 35 pressed plate is less than might be obtained with a more advantageous distribution of the metal. Another objection to such constructions as heretofore manufactured is that

40 the panels or other portions of the metal which are in spaced planes are connected to each other by obliquely extending intermediate portions instead of being connected by webs perpendicular to the planes of the 45 panels. The reason for this is that it is practically impossible to press such plates so that these intermediate portions are always more or less inclined.

To overcome the conditions as above stated 50 I have devised a construction of car wall which is formed of rolled plates, said plates being provided with panel portions in

spaced planes connected by intermediate portions substantially perpendicular thereto and the construction is also one in which the 55 gauge of the metal in the panel portions and intermediate portions is uniform while the cross section at the corners is increased and extends to the plane of the outer face of each panel. Such a rolled plate will have a very 60 considerable degree of additional strength over any pressed plate which can be produced from the same weight of metal.

A further feature of my improvement is the carrying of this spaced paneled construction to the corner of the car and providing at such corner a post so fashioned that it will cap the ends of the panels and 65 form a weather-proof joint therewith.

In detail A is a rolled metal plate having the parallel spaced panel portions B, B' connected to each other by an intermediate web portion C which is substantially perpendicular to the planes of said panels. The 70 corners D and D' are of increased cross section each of the opposite faces of the web C extending in the same plane to the plane of the outer face of the panel. This distribution of metal which may be readily made in 75 rolling but which would be impossible in pressing, greatly increases the strength of the truss as does also the arrangement of the web C in a plane perpendicular to the planes of the panels.

As shown in Figure 5 the plate A is rolled 80 with one full panel B' in one plane and two half panels B in the spaced planes. These half panels are extended as indicated at B² sufficiently to form an overlap so that the adjacent plates may be secured to each other 85 by riveting. With such a rolled plate construction a car end may be formed from the series of plates A', A², A³, A⁴ riveted to each other along the lines E and covering the intermediate area of the car end.

90 F are posts arranged at the corners of the car and so fashioned on one side as to conform to the paneled plates and to cap the ends thereof. Thus, as shown, the posts F have portions F' for fitting against the inner 95 panels of the plates, portions F² for fitting against the outer panels of the plates and intermediate portions F³ for fitting around the web portions C of the plates. In addition

tion the posts are provided with a flat angle flange F² for bearing against the side wall of the car body. Such posts are preferably steel castings which may thus be readily fashioned to conform to the plates.

The car end constructed as above described may be provided with a wooden lining G. This may be secured to wooden inserts H which are placed in the channels formed by the outer panels and may be secured therein by suitable means such as the bolts J. The lining G may also be formed of relatively thin stock inasmuch as it is bearing against the metal panels and wooden inserts throughout its entire length and is thus strongly reinforced.

While I have specifically described a car end it is obvious that the same construction might be used in other portions of a car wall. It is also obvious that the panel plate may be arranged as shown in Figure 3 or may be in reverse position or, in other words, either series of panels may be arranged on the outside of the car.

What I claim as my invention is:

1. A car wall comprising a rolled metal plate having spaced parallel panel portions and intermediate portions substantially perpendicular thereto.

2. A car wall comprising a rolled metal plate having spaced parallel panel portions, intermediate web portions substantially perpendicular to said panels and corners at the intersection of said panels and web which are of increased cross section.

3. A car wall comprising a rolled metal plate having panel portions in spaced parallel planes, intermediate web portions substantially perpendicular to said panel portions and corners which extend substantially

to the line of intersection of the outer faces of said panels and webs.

4. A car wall comprising a metallic plate having alternate, transversely extending panels in spaced parallel planes with intermediate webs substantially perpendicular to said panels, the cross section of said plate being uniform to its end and a corner post at the end of said plate fashioned to conform to said panels and web and to form a weathering cap therefor.

5. A car wall comprising a rolled metal plate having transversely extending panels alternately in spaced parallel planes with intermediate web portions substantially perpendicular to said panels and a corner post of an angle cross section having one of the flanges thereof fashioned to fit about said panels and webs and to form a weathering cap therefor.

6. A car wall comprising a series of rolled paneled plates each plate having a full panel in one plane and a pair of panels of less width in a spaced plane with substantially perpendicular web portions connecting the said panels, the adjacent plates of the series being connected to each other by overlapping and connecting narrow panels to form panels equal in width to said full panels.

7. A car wall comprising a rolled metal plate having alternate transversely extending panels in spaced parallel planes with intermediate webs substantially perpendicular to said panels, a cross section of said plate being uniform to its ends, and means at the end of said plate for weather capping the same.

In testimony whereof I affix my signature.

WILLIAM D. THOMPSON.

CERTIFICATE OF CORRECTION.

Patent No. 1,641,208.

Granted September 6, 1927, to

WILLIAM D. THOMPSON.

It is hereby certified that the State of Incorporation in the above numbered patent was erroneously given as "Michigan" whereas said State should have been given as "Delaware" as shown by the records of assignments in this office; and that the said Letters Patent should be read with this correction therein that the same may conform to the record of the case in the Patent Office.

Signed and sealed this 11th day of October, A. D. 1927.

Seal.

M. J. Moore,
Acting Commissioner of Patents.
